UNITED STATES PATENT OFFICE.

WILLIAM F. TEMPLE, OF ELSBERRY, MISSOURI, ASSIGNOR OF ONE-FOURTH
TO O. E. TEMPLE, OF SAME PLACE.

ROTARY ENGINE.

SPECIFICATION forming part of Letters Patent No. 642,644, dated February 6, 1900.

Application filed June 21, 1897. Serial No. 641,703. (No model.)

To all whom it may concern:

Be it known that I, WILLIAM F. TEMPLE, residing at Elsberry, in the county of Lincoln and State of Missouri, have invented a new and useful Rotary Engine, of which the following is a specification.

My invention relates to improvements in rotary engines; and the object thereof is to provide an engine which is simple in construction and can be run at an increased speed. I accomplish this by providing the casing with a plurality of steam inlet and outlet spaces oppositely arranged on the interior thereof and mounting a piston within the chamber, so as to form a space on each side thereof. The steam-inlet spaces are in communication with the spaces on one side of the piston, so that when steam is supplied to the casing it will enter these spaces and operate the piston from a number of points instead of one, as heretofore. The outlet-passages are preferably arranged alternate with the inlet-passages, so that as the pockets containing live steam pass over them it is exhausted. In this manner after the greatest force of the steam has been exerted on the piston it is immediately exhausted and not carried around in the casing, as ordinarily, thereby doing away with a great deal of resistance. In order that my invention may be fully understood, I will proceed to describe the same with reference to the following drawings, in which—

Figure 1 is a perspective view of a rotary engine constructed in accordance with my invention. Fig. 2 is a sectional view thereof, taken on the line 2 2 of Fig. 3. Fig. 3 is a transverse section taken on the line 3 3 of Fig. 2. Fig. 4 is a sectional view taken on the line 4 4 of Fig. 3; and Fig. 5 is a similar section taken on the line 5 5 of Fig. 3. Fig. 6 is a detail view.

In the said drawings, A represents the casing of my improved rotary engine, and B the flange thereof, suitably mounted on the base C. The casing A is provided with the steam-inlet D on one side thereof and with the exhaust E on the other side thereof. The two are separated by means of the projections, 50 hereinafter referred to, and the piston which

revolves within the casing, as will be more fully explained. The interior of the casing is provided with a number of projections F, which form the steam-spaces G and the exhaust-spaces H. They are arranged alternately, as shown in Fig. 2, and the steam-passages are in communication with one side of the casing, while the exhaust-passages are in communication with the other. The advantage of having the four steam-spaces arranged at equidistant points is that the strain on the piston is distributed and a greater speed is obtained. The advantage of the four exhausts is that the steam-pockets of the piston are quickly emptied of steam, so that there will be little or no resistance.

I represents the piston, formed of the side flanges I' and the inclined blades I². It is located centrally in the casing, so as to form a space on either side thereof, and it is secured on the shaft J by means of the flange J' and bolts J², which pass through the flange J' and a flange K on the shaft J. The shaft passes through the casing, and at those points the stuffing-boxes L are provided, and its ends are journaled in the standards at the top of the standards M. The boxings M' are so arranged that the joint between the cap-plate and the stationary part is not in line with the pull of the belt, so that the strain on these parts is to a great extent avoided.

As seen from the drawings, the piston projections F and the ends F' of the steam and exhaust spaces prevent the live and exhaust steam intermingling, so that the live steam 85 will enter the pockets of the piston and perform work and then escape through the exhaust-spaces into the exhaust side of the casing.

The operation of my device will be readily understood. The steam enters the casing on one side of the piston and passes into the steam-spaces and into the pockets of the piston to rotate it. As the pockets of the piston pass the exhaust-spaces the steam escapes 95 into them and passes out on the other side of the piston through the exhaust D.

From the foregoing it will be seen that I have produced a rotary engine which, owing to its simplicity and increased number of 100

steam inlet and outlet passages, will run at an increased speed.

It will be understood that I do not limit myself to the precise number of steam inlet 5 and outlet passages nor to the exact arrangement of piston, as there could be a greater or less number and slightly-different arrangement of piston without departing from the spirit of my invention. I also preferably have 10 the side plates of the casing removable, so that the interior of the engine can be easily seen.

On each side of the piston-head is a plate or head N, secured thereto by bolt O, said 15 head or plate extending beyond the circumference of the piston-head and bolted to the parts F' between the live-steam and exhaust openings of the cylinder. These heads are notched, one of them to conform to or register 20 with the live-steam openings and the other to the exhaust-openings, and have suitable stuffing-boxes around the shafts.

Having thus fully described my invention, what I claim as new, and desire to secure by 25 Letters Patent, is—

1. In a rotary engine the combination with the driving-shaft, of a piston suitably mounted thereon provided with a series of tangential blades forming pockets between them, an 30 outer casing provided with an interior annular projection adapted to fit against the periphery of said piston, a series of spaces or pockets provided in the said annular projection and communicating with the piston- 35 pockets and alternately communicating with

the inlet and outlet chambers respectively, substantially as described.

2. The combination with the driving-shaft provided with an annular flange, of a piston provided with an annular flange adapted to 40 be secured to the said driving-shaft flange, a series of tangential blades formed in the said piston, a casing provided with an annular projection adapted to fit against the periphery of said piston, a series of spaces or pockets 45 provided in said annular projection communicating with the piston-pockets and alternately communicating with the inlet and outlet chambers respectively, and a pair of circular disks provided on the sides of the piston-head extending beyond the circumference of said piston-head and bolted to the annular projection of the casing, substantially as described.

3. The combination with the driving-shaft 55 of a rotary engine, of a casing suitably mounted thereon, an inlet and outlet chamber provided in said casing, a rotary piston detachably connected to said driving-shaft, a series of tangential blades provided in said piston, 60 and a series of spaces or pockets provided in the said casing communicating with the piston-pockets and alternately communicating with the inlet and outlet chambers respectively, substantially as described.
